(57) **CLAIM**

The ornamental design for a magnetic resonance tomography diagnosis apparatus, as shown and described.

DESCRIPTION

FIG. 1 is a first perspective view of a magnetic resonance tomography diagnosis apparatus showing our new design; FIG. 2 is a second perspective view thereof;

FIG. 3 is a rear perspective view thereof,

FIG. 4 is a front elevational view thereof,

FIG. 5 is a rear elevational view thereof,

FIG. 6 is a top plan view thereof,

FIG. 7 is a bottom plan view thereof,

FIG. 8 is a left side elevational view thereof,

FIG. 9 is a right side elevational view thereof,

FIG. 10 is a cross-sectional view thereof; taken along line 10-10 in FIG. 4;

FIG. 11 is a cross-sectional view thereof; taken along line 11-11 in FIG. 4;

FIG. 12 is an enlarged view of the part partitioned by 12-12 in FIG. 4;

FIG. 13 is an enlarged view of the part partitioned by 13-13 in FIG. 10; and,

FIG. 14 is an enlarged view of the part partitioned by 14-14 in FIG. 11.

The broken lines in the figures show portions of the magnetic resonance tomography diagnosis apparatus which form no part of the claimed design.
